FLY TRAP

David H. Robinot, New York, and Alex Weil,
Jamaica, N.Y.

Application April 26, 1941, Serial No. 390,460

14 Claims. (Cl. 43—114)

This invention relates to insect extermination, and more particularly for devices for trapping or catching insects, particularly flies.

One of the objects of this invention is to provide a device of the above-mentioned character that will be of simple and inexpensive construction and assembly and that will be of dependable and efficient action in use. Another object is to provide a device of the above-mentioned character that can be constructed in relatively small form, that will be neat, clean and attractive in appearance and thus avoid the unsightliness and other disadvantages of many devices, such as sticky fly paper or ribbons, now principally available on the market, and that can be readily placed in a wide variety of locations.

Another object is to provide a device of the above-mentioned character in which unsightliness and like disadvantages of known devices may be dependably overcome and in which, in contrast to such known devices, attractiveness and uniqueness of appearance are achieved in a way that will enlarge its use or application in places or locations, for example, in a show window or show case displaying food products, where heretofore known expedients, such as fly paper, either are not at all employed or, if employed, are unsightly and distasteful. Another object is to provide a fly-trapping device in which certain functional elements can be made to provide, or add to, attractiveness, cleanliness or neatness of appearance.

Another object is to provide a device of the above-mentioned character so constructed as to facilitate manufacture, assembly, replacement of parts, cleaning and the like. Another object is to provide a device of the above-mentioned character in which a luring or attraction thereto of flies may be achieved in a simple, dependable and efficient manner. Another object is to provide a device of the above-mentioned character in which "eye-appeal" or attraction of flies by use of their sense of sight may be effectively utilized. Another object is to provide a device of the above-mentioned character in which luring thereto of flies by their sense of smell and by their sense of sight may be brought about with good effect and in a simple, compact attractive and dependable structural manner.

Another object is in general to provide an improved fly-catching device, and to provide a device capable of wide application in practice. Other objects will be in part obvious or in part pointed out hereinafter.

The invention accordingly consists in the features of construction, combinations of elements,

and arrangements of parts as will be exemplified in the structure to be hereinafter described and the scope of the application of which will be indicated in the following claims.

5 In the accompanying drawing, in which are shown several of the various possible embodiments of our invention,

Figure 1 is a front view of a preferred embodiment of our fly-trap constructed in accordance with the present invention.

10 Figure 2 is a plan view as seen from above in Figure 1, certain parts being broken away to show the interior construction.

Figure 3 is a vertical cross-sectional view, the section being taken on line 3—3 of Figure 2.

15 Figure 4 is a top plan view of a baffle insert used in the construction of Figures 1, 2 and 3.

Figure 5 is a horizontal sectional view of a modified form of this invention, the section being taken on line 5—5 of Figure 6.

20 Figure 6 is a vertical sectional view as seen along the line 6—6 of Figure 5.

Figure 7 is a top plan view of a baffle insert used in the modified form of Figures 5 and 6; and

25 Figure 8 is a view similar to Figure 7 and showing another modified form of baffle insert, a part thereof being broken away.

Referring in greater detail to the drawing and more particularly to Figures 1—3, the fly-trap or lure is preferably of casing-like or box-like construction, illustratively four-sided, and it is preferably made up of a lower part 10 and an upper part 9; the lower part 10 has a bottom or floor 11 having extending upwardly at right angles therefrom four side walls 14, 15, 16 and 17 which may, if desired, be formed integrally with the bottom 11. The upper part 9 comprises a top wall or cover 12 having extending downwardly therefrom at right angles four walls, 31, 32, 33 and 34 which may, if desired, be formed integrally with the top wall 12 and which, when the top part 9 is assembled to the lower part 10, take over the upper sides of the walls 14, 15, 16 and 17, in a manner similar to that of a conventional box. An eyelet 18 is secured to the floor 11 into which may be engaged a nail, hook or other desirable and suitable object by means of which the trap may be suspended from a wall or other surface, if desired.

30 50 The top wall or cover 12 is provided with an opening 35 which is preferably circular and centrally positioned, as appears better from Figure 2, and coacting with the opening 35 is a baffle member 29 suitably supported within the closed housing and preferably supported by the lower casing

part 10 and in spaced relation to the bottom or floor 11; for supporting the baffle member 29 in one form, we provide a secondary wall element 19 which is glued or otherwise secured to the inner face of the walls 14, 15, 16 and 17. As better appears in Figure 2, the wall element 19 has four portions or secondary walls, one for each of the side walls of the casing part 10, being identified in the drawing by the numerals 20, 21, 22 and 23 respectively. Each of the secondary walls is provided, near its upper edge and substantially centrally, with a horizontal slot 24 adapted to receive the free ends 25, 26, 27 and 28, of the baffle member 29 which is made of a transparent and light-reflecting material. Baffle insert 29 is illustrated in Figure 4 as being substantially square initially and provided at its four corners with cut-outs 36, thus to leave, intervening the cut-outs, the several free end or support-engaging members to be received in the slots 24 of the internal or secondary wall element 19 referred to above. At its center, the baffle may be curved upwardly to form an upright, bulbous dome 38 for a purpose to be presently described. Baffle member 29 when assembled to the lower casing part 10, thus has its dome 38 substantially centered with respect to the casing and, as shown in Figure 3, the top of the dome 38 preferably falls in the region of the plane of the cover or top wall 12 when the upper casing part 9 is put in position; top wall or cover 12, being provided, as above noted, at its center with the circular opening 35, becomes positioned above the plane of the flat portion of the baffle member 29 as better appears in Figure 3, the space between the two being peripherally closed by the walls of the lower part 10. The opening 35 is preferably proportioned relative to the dome 38 substantially as shown in the drawing, from which it will be seen that the dome has a wide range of visibility through the opening 35, and being light-reflecting, appears bright in comparison to other parts and thus attracts flies by their sense of sight. It will also be noted (see Figures 2 and 3) that the relationship of these two parts provides an entry passageway into the above-mentioned space between the top wall 12 and the flat portions of the baffle 29, for the entry thereinto of flies, while the cut-outs 36 (Figures 4 and 2) provide passageways from that space into the lower interior and hence into the space between the baffle member 29 and the bottom or floor 11 of the housing.

Below baffle member 29 and hence in the space between the latter and the bottom 11, we provide suitable means to lure or attract the fly downwardly through the passages formed by the cut-outs 36, and such a means preferably functions by way of its odor to lure the fly by its sense of smell; thus, for example, with its bottom resting on floor 11 of the housing, is a dish or cup-like member 39 made of paper or other suitable material for containing a suitable lure substance; thus the member 39 at its upper surface, may be provided with a layer or coat 40 of odorous material, its odor being such as is calculated to attract flies.

As appears clearly from Figures 2 and 3, the container or member 39 may conveniently be in general of circular shape, fitting in between the four side walls of the housing structure, with its bottom 42 resting against the bottom 11, while its side walls may be of any convenient configuration, such as frusto-conical and terminating in a peripheral flange as indicated at 41 in Figure 3.

In the modified form illustrated in Figures 5 to 75

7 inclusive, the fly trap has a bottom part 50 with side walls, illustratively four in number, as in Figures 1-3, and an upper part 51 with depending side walls, illustratively four in number, to take over the side walls of the lower part 50, the top wall provided by the upper part 51 being provided with a central opening 52.

Instead of mounting the baffle member, in this form, by means of the secondary walls described in connection with the form of Figures 1-3, the four side walls of the lower casing part 50 (Figures 5-6) are provided with horizontal slots near the upper edges thereof for the reception of edge portions or free ends of the baffle member, and to illustrate that the baffle member may take other forms than that described in connection with Figures 1-4, we may use a baffle like the baffle 53 of Figure 7 which may be initially square and have its four corners clipped off to provide free ends or support-engaging portions 54 for entry into the side wall slots in a manner comparable to the entry of the free ends 25, 26, 27, 28 of baffle 29 in the slots 24 of Figures 2 and 3. In Figures 5 and 6, the slots in the side walls are shown at 55, with the end elements 54 of the baffle 53 received therein.

Another form of baffle insert is illustrated in Figure 8 where there is employed a baffle insert 53a made of wire mesh, which may be nickel plated or brass plated or treated in any other desirable manner to render it light-reflecting. Here too, the corners are shown as being clipped off, to provide support-engaging portions or free ends 54a.

The container or receptacle 39 is provided with a suitable substance as above pointed out, and this may be supplied to the container 39, or a container thus provided with such a substance inserted into the lower casing part 11, after having first removed the upper part 9 and also the baffle 29, whence the baffle is replaced by entering the four free ends in the four retaining slots and the cover is again placed upon the box. The odor of the substance within the trap will attract flies, as will the dome of the transparent and light-reflecting baffle insert. The bright surface of the baffle member 29 and particularly of its dome 38 in effect guides the flies, using their sense of sight, to or through the opening 35, and they come to rest on the upper surface of the baffle member 29, being further lured by the odor of the substance in the container 39. Flies will enter the space between the baffle 29 and the bottom 11 of the box via the openings created by the cut-outs 36 in the baffle insert.

Reaching the interior through the apertures formed by the cut-outs 36, as above mentioned, flies proceed to the substance 40, being attracted thereto by its odor, and depending upon the character of the substance 40, final disposition of the flies may thereupon ensue; for example, if the substance 40 is gummy or sticky, as is illustratively set forth above, they become attached thereto as soon as they land or crawl onto it. Should they not become disposed of in that manner, escape from the space below the baffle member 29 does not take place, excepting in the infrequent instance or instances where a fly or flies should by chance or accident find its way out of that space through one of these corner openings provided by the cut-outs 36. The chance of the latter happening, however, is quite small, due to certain relationships and coactions present in the construction.

For example, the cover wall 12 of the upper

housing part 9, where it is not cut away by the opening 35, suitably overlies these corner openings, and thus darkens them, the darkening effect, when considered from within the space below the baffle member 29, being enhanced by the relatively large amount of light, entering through the opening 35 in the cover wall 12, that is thereby concentrated upon the central portion or areas, including the dome 38, of the baffle member 29. As a result the flies, within the space below the baffle 29, are guided or led, by their sense of sight, upwardly (see Figure 3) to this central and relatively concentrated area of light, an effect that may be enhanced in turn by the action of the material of the baffle member 29 and also by the shape of the dome 38, upon the light rays. Thus flies that are still free or able to fly or move around and which seek escape, concentrate their efforts quite substantially to the underside of this central portion of the baffle member, underlying the opening 35, and where the baffle member is shaped to provide an upwardly extending but downwardly open pocket such as the concave interior of the dome 38, the flies tend to concentrate in that pocket or an individual fly concentrates its efforts therein. And in this connection it might be noted that, as appears from Figure 3, the walls of the pocket formed by the dome 38, progressively rising toward or into the opening 35 in the cover wall 12, are thus in effect brightest or of greatest light intensity at the region of the apex, and this effect tends to attract the fly or flies more and more to the apex. Flies that drop or fall from the underside of the baffle member 29 are received by the cup 39. When the cup is sufficiently full of flies, the cover of the trap is removed as is the baffle, the cup is disposed of and another cup substituted for it, which has prior thereto received a coating of the gummy substance. When this is done, the baffle and cover are again replaced and the device is ready for continued use. When the device is put on the market, it may be sold with a collapsible tube of the gummy substance which can then be readily applied.

The illustrative modified form of the trap differs in the baffle mounting in that the retaining slots for the baffle insert are positioned directly in the walls of the housing. When the baffle member 53 is inserted, its free ends 54 enter the slots 55 in the lower casing part 50 and become flush with the outer surfaces of lower part 50, and when the upper part 51 with its depending side walls, is placed upon the box, it aids in firmly retaining the baffle in operative position.

In order to enhance the effectiveness of the trap at night or in a dark place, it may be desirable to provide a phosphorescent spot in the dome of the baffle insert or anywhere else on the insert or around the edges of the dome or around the circular opening of the cover or at any other advantageous point.

Many modifications not shown in the drawing become apparent, and others will become apparent in the course of time. For instance, the baffle insert illustrated in Figure 4 may be made in the shape shown in Figure 7, that is to say, the baffle shown in Figure 7 may be provided with a dome, and the inserts shown in Figures 7 and 8 may be made in the shape shown in Figure 4, that is to say they may be provided with free ends instead of clipped corners, and the box may be made in other forms and not only square. Furthermore, it may be desired to paint an orna-

mental design or designs upon the box, in order to render it decorative.

It will be understood, therefore, that the foregoing is to be regarded as illustrative and descriptive only of preferred embodiments of the invention, and it will be clear that changes in the construction of the invention may be made within the scope of the appended claims, without departure from the spirit of the present invention.

Having thus described the invention, what is claimed as new and desired to secure by Letters Patent, is:

1. A fly-trap comprising a casing having opposed top and bottom walls, and side walls, with a substantially centrally positioned opening in said top wall for the passage into the interior of the casing of insects and of light, a baffle member within said casing and extending crosswise thereof and spaced intermediate of said top wall and bottom wall and presenting a substantially central area thereof below said opening for receiving light entering the case through said opening and other portions thereof below those parts of the top wall that extend about said opening, said other portions being shielded by said parts of said top wall against material illumination thereof, whereby said central area receives maximum light through said opening and said other portions of said baffle member are in contrast to said central area relatively dark, said central area of maximum light of said baffle member having the characteristic of transmitting light therethrough and said other portions thereof that are relatively dark having means forming a passage for insects to the space between said baffle member and said bottom wall, whereby said passage-forming means are located in a region relatively dark as compared to the light intensity of said central area, said central area of said baffle member, due to its light-transmitting characteristic and due to light it receives through said opening, acting by way of the contrast to the dark region of said passage-forming means to attract insects within said last-mentioned space away from said passage.

2. A fly-trap comprising a closed casing having in a wall thereof an opening for the passage therethrough of insects and of light, said opening being of lesser area than said wall, means within said casing and remote from said opening for supporting an insert lure, baffle means made of a light-transmitting material interposed between said wall and said means and sub-dividing the interior of said closed casing into two spaces in one of which is said lure-supporting means and to the other of which said opening forms an entry thereto for insects and for the passage of light rays to said baffle means, said baffle means having a configuration so that certain portions are more remotely spaced from said opening than are other portions thereof, thereby to vary the intensity of light striking said baffle means and to cause portions thereof to appear, from within the space containing said lure-supporting means, of greater light intensity than others and thereby attract insects thereto, and means located at portions of said light-transmitting baffle means that are more remote from said opening forming a passage for insects to said last-mentioned space and hence to said lure, the portions of said light-transmitting baffle means that are at greater light intensity attracting insects in said space that contains said lure-supporting means away from said passage-forming means.

3. A device as claimed in claim 2 in which said

baffle means comprises a substantially flat member made of said light-transmitting material, said member being of an extent to underlie said wall and said opening, whereby the portions of said member substantially juxtaposed to said opening are of greater light intensity and other portions thereof that underlie said wall and are more remote from said opening are of lesser light intensity.

4. A device as claimed in claim 2 in which said baffle means comprises a member made of said light-transmitting material and having a portion juxtaposed to said opening formed to provide a pocket opening into the space containing said lure with the bottom portions of said pocket nearest said opening, thereby to provide said portions of greater light intensity.

5. A device as claimed in claim 2 in which the portions of said baffle means underlying said opening converge to an apex substantially coaxially aligned with said opening.

6. A fly-trap comprising a two-part box-like casing having two opposed walls, one on each of the two parts, one of said walls having a substantially centrally positioned opening for entry of insects and of light, means in said casing for retaining a lure in the region thereof adjacent the other of said opposed walls, a baffle member for sub-dividing the interior of said casing into a space adjacent said one wall and its opening and another space bounded by said baffle member and said other wall, at least that portion of said baffle member juxtaposed to said opening being of a light-transmitting medium to receive light from said opening and to appear, from within said second-mentioned space, as a relatively bright area or region as compared to the portions of said baffle member underlying said one wall, the latter shielding said portions of said baffle member against material illumination there being means at the regions of said baffle member underlying said one wall forming a passageway for insects from said first space to said second space when attracted by the lure in the latter, and means supporting said baffle member within said casing.

7. A device as claimed in claim 6 in which said means for supporting said baffle member comprises a plurality of elements distributed about said baffle member, said casing being provided with recess means for receiving said elements of said baffle member.

8. A device as claimed in claim 6 in which said means for supporting said baffle member comprises a plurality of end portions distributed about said baffle member, the side walls of said casing having slot means for receiving said end portions of said baffle member.

9. A device as claimed in claim 6 in which said means for supporting said baffle member comprises a plurality of end portions distributed about said baffle member, said casing having in-

ternally thereof secondary side walls provided with means with which said end portions of said baffle member detachably engage.

10. A device as claimed in claim 6 in which said means for retaining said lure comprises a receptacle, removably seated within said second space, whereby upon separation of said two-part casing, said receptacle may be replaced.

11. A device as claimed in claim 6 in which said means for supporting said baffle member comprises a plurality of elements distributed about said baffle member, one part of said casing comprising side walls and one of said opposed walls, said side walls having slot means for respectively receiving said elements, and the other part comprising the other of said opposed walls with depending side wall portions telescoping over said side walls containing the slot means and of sufficient length to close said slot means off externally.

12. A device as claimed in claim 6 in which the portion of said baffle member juxtaposed to said opening is conformed to have walls converging toward an axis aligned with said opening whereby different portions of said walls are of different distances from said opening and receive through the latter differing intensities of light.

13. A device as claimed in claim 6 in which the portion of said baffle member underlying said opening is substantially dome-shaped with its apex in the region of the plane of said one wall.

14. A fly-trap comprising a closed casing having opposed top and bottom walls, with baffle means sub-dividing the interior of said casing into an upper space adjacent said top wall and into a lower space adjacent said bottom wall, said top wall having an opening for the passage therethrough of insects and of light and said baffle means having a portion substantially juxtaposed to said opening, said portion bulging upwardly in a direction toward said opening but without closing said opening, said upwardly bulging portion that is exposed toward said opening being light-reflecting, thereby to appear relatively bright and to attract insects by their sense of sight, means within said lower space for holding an insect lure, means at those regions of said baffle means that underlie said top wall providing passage for insects from said upper space to said lower space and the lure in the latter, said upwardly bulging portion of said baffle means also having the characteristic of transmitting light and thereby appearing, from within said lower space, brighter than other portions of said baffle means, thereby to form a lure to attract insects in said lower space away from said passage-providing means.
